UNITED STATES PATENT OFFICE.

BORIS TUCKER, OF BROOKLYN, NEW YORK, ASSIGNOR OF ONE-HALF TO SAMUEL GREENSTEIN, OF BROOKLYN, NEW YORK.

FEEDING DEVICE FOR PRODUCING SPIRAL STITCHES.

Application filed August 5, 1921. Serial No. 490,060.

To all whom it may concern:

- Be it known that I, BORIS TUCKER, a citizen of the United States of America, and a resident of the city of New York (borough 5 of Brooklyn), in the county of Kings and State of New York, have invented a new and Improved Feeding Device for Producing Spiral Stitches, of which the following is a full, clear, and exact description.
- 10 My invention has for its object to provide means for automatically moving, relatively to a sewing machine, a holder in which the goods are disposed during the sewing process.
- 15 Still further objects of the invention are to provide a construction having means for operating the work holder to produce a spiral stitch, the construction being such that it may be readily attached to a sewing 20 machine; to provide adjustable means for moving the work holder at a predetermined speed relatively to the speed of the sewing machine; to provide an improved holder in which the goods are disposed during the 25 sewing process and to provide means for disconnecting the work holder from its operating means as soon as it reaches a predetermined point relatively to the sewing machine.
- 30 Additional objects of the invention will appear in the following specification, in which the preferred form of my invention is described.

In the drawings similar reference characters refer to similar parts in all the views of which—

Figure 1 is a front elevation of my invention.

Figure 2 is a plan view of Figure 1.

40 Figure 3 is a transverse sectional view of Figure 1.

Figure 4 is an enlarged fragmentary sectional view illustrating the gearing by which the speed of the work holder may 45 be controlled relatively to the speed of the sewing machine.

Figure 5 is a fragmentary view illustrating the stitching.

Figure 6 is an enlarged plan view illustrating a modified form of the work holder.

Figure 7 is a sectional view on the lines 7—7 of Figure 6.

By referring to the drawings it will be seen that parts of a sewing machine are 55 illustrated as, for instance, a sewing ma-

chine frame 10, a head 11 and a foot 12. My device has a frame 13 with a horizontal portion 14 which is adapted to be disposed against the bottom of the frame 10 and be held in position by means of the 60 screw 15, which is disposed through an orifice 16 in a work rest 17 and through an orifice 16^a in a depending portion 18 of the frame 14, and through an orifice 16^b in the frame portion 14, the bolt 15 having a 65 thread meshing in a threaded orifice 19 in the frame 10. The work rest 17 is secured to the depending portion 18 of the frame.

The frame 13 has extending and vertically disposed portions 20 and 21, having 70 bearings in which is journaled a shaft 22; this shaft carrying a pulley 23 which, as will be seen by referring to Figure 3 of the drawings, is engaged by a sewing machine belt 24 by which means the shaft 22 is rotated. Journaled in bearings 25 in the frame 13 there is a shaft 26 which is driven by shaft 22 by means of gearing 27, the said shaft 26 being a means for driving the shaft 28 by means of the gearing 29. The 80 said shaft 28 is journaled in bearings 30 in the frame 13. Mounted on this shaft 28 there are gears 31, 32 and 33 which differ in diameter as is best shown in Figure 4 of the drawings. There is a slot 34 in the 85 shaft 28 which is hollow, and disposed in this slot 34 there is a key 35 which is mounted on a spring 36 secured to the stud 37 at 37^a. This key 35 is provided for engaging any one of the recesses 38 in the gears 31, 90 32 and 33. It will be understood that when this key 35 engages the recess 38 in the gear 33 as shown in Figure 4 of the drawings, that the said gear 33 will rotate with the shaft 28 and that when it is out of engagement with the gear 33 and is disposed in the recess 38 in the gear 32 that the gear 32 95 will rotate with the shaft 28 instead of the gear 33. By this means any one of the gears 31, 32 and 33 may be secured for rotating 100 with the shaft 28. The key 35 is curved so that it may be pushed inwardly or outwardly into or out of engagement with any one of the gears 31, 32 and 33, and as a means for indicating the position of the key 105 35 relatively to the recess 38 in one of the gears I provide the stud 37 with annular grooves 39, and I provide the gear 29^a with a circular groove 40 in which a circular spring 41 is disposed, it being understood 110

that when the stud 37 is pressed inwardly the spring 41 will expand out of the annular groove 39 in which it has been disposed and will slide on the stud 37 until it reaches the 5 next annular groove 39.

In bearings 42 in the frame 13 there is journaled a shaft 43, gears 44, 45 and 46 being keyed to this shaft 43, the gear 44 meshing with the gear 31, the gear 45 meshing 10 with the gear 32 and the gear 46 meshing with the gear 33. This shaft 43 has a thread 47.

The bottom 48 of the work holder 49 illustrated in Figures 1, 2 and 3 of the drawings has a depending member 50 with a bearing 51, in which a stud 52 is disposed, this stud 52 having a tooth 53 for engaging the thread 47 of the shaft 43. Around the stud 52 there is a spring 54 which engages the 20 bearing 51 and the collar 55 on the stud 52 for holding the tooth 53 yieldingly in engagement with the thread 47.

As will best be seen by referring to Figure 1 of the drawings, there is a horizontal slot 25 56 in the frame 13 and slidably in this slot 56 there is a means for securing a bracket 57 to the frame 13 in an adjusted position, the said bracket 57 having a bifurcated cam 58 for engaging the button 59 on the stud 30 52 and pressing the stud downwardly so that its tooth 53 will be disengaged from the thread 47 when the work holder 49 is moved to a predetermined position relatively to the sewing machine. By this means 35 the movement of the work holder relatively to the sewing machine may be stopped when the work holder reaches a predetermined position relatively to the sewing machine.

The bottom 48 of the work holder is provided with a slot 60 and a bracket 61 is 40 adjustably secured to the said bottom member 48 of the work holder by means of a bolt 62 which passes through an orifice in the bracket 61 and is disposed in the slot 60; a nut 63 engaging the bolt 62 below the 45 bottom member 48 of the work holder. The upper member 64 of the work holder is hinged to the bracket 61 at 65, the forward and rear of the upper member of the work 50 holder being bent downwardly to engage the work 65 and to keep a certain amount of pressure on the work 65 as it passes through the work holder 49. The bottom member 48 of the work holder has a guide 66 and the upper member 64 of the work 55 holder has a guide 67, these guides being disposed between the bottom and the upper members of the work holder to guide the goods through the work holder. The upper member 64 of the work holder also has a depending projection 68 for engaging the sides of the bottom member 48 and the bottom member 48 has upwardly extending projections 69 for engaging the sides of the 60 upper member 64, these projections 68 and

69 being preferably continuous of the guides 66 and 67. The upper member 64 also has a locking member 70 which is provided with a slot 71 in which a set screw 72 is disposed, this set screw meshing in a threaded orifice 70 in the upper member 64. To the bottom member 48 of the work holder there is secured a bracket 73 having a bearing 74 in which a stud 75 is disposed, this stud 75 being adapted to engage the locking member 70 at a recess 76. There is a bayonet slot 77 in the bracket 73 in which a member 78 is adapted to travel, this member 78 being screwed to the stud 75. It will be understood that when this member 78 is 80 moved rearwardly and turned to one side, it will hold the stud 75 out of engagement with the recess 76 in the locking member 70. There is a spring 79 in the bearing 74 which holds the stud 75 yieldingly forward. The adjustable arrangement for securing the locking member 70 to the upper member 64 of the work holder is provided so that when the upper member 64 of the work holder is 85 moved and is secured in an adjusted position with the guides 66 and 67 a predetermined distance apart by means of the adjustment of the bracket 61 relatively to the bottom member 48 of the work holder that the locking member 70 may also be adjusted so that the stud 75 will engage the recess 76 therein. Extending from the depending member 50 there is an arm 80 for holding the goods which are being sewed out of contact with the depending member 50 and the shaft 43, so that the material, when it leaves the material rest 17, will be brought forward before it passes through the work holder 49. 90

In the modified form of the work holder as shown in Figures 6 and 7 of the drawings it will be seen that the bottom member 85 has sides 86 and lugs 87, there being recesses 88 in the lugs 87 in which are normally disposed studs 89 which are held in bearings 90 in a transverse member 91, secured to the top of the upper member 92 of the said work holder. The studs 90 are held yieldingly away from each other by a spring 93 and said studs may be drawn inwardly and out of the recesses 88 by means of the buttons 94 which are secured to the studs and which project through slots 95 in a transverse member 91. As has been said with reference to the work holder illustrated in Figures 1, 2 and 3, the upper member 92 of this work holder is bent downwardly at its forward end 96 and also at its rear end 97 for engaging and holding work as it passes through the work holder. 100

The handle 37^e is rotatably mounted on the stud 37, and by means of this handle 37^e the stud may at all times be conveniently adjusted. 110

What I claim is:—

1. In a feeding device for producing 120

- spiral stitches, a frame adapted to be secured to the frame of a sewing machine, a shaft journaled in a bearing in the first frame, means for rotating the shaft adapted 50
5 to be engaged by a moving part of the sewing machine, a second shaft, means by which the second shaft is adapted to be rotated by the first shaft, a third shaft having a thread, a plurality of gears of different diameters 55
10 secured to one of the last two mentioned shafts, a plurality of gears of different diameters meshing with the first gears and mounted on the other of the said last two mentioned shafts, selective means to secure 60
15 a predetermined gear of the last mentioned gears to the shaft on which it is mounted and a work holder having a tooth for engaging the thread on said third shaft. 65
2. In a feeding device for producing a spiral stitch, a frame adapted to be secured to a frame of a sewing machine, a shaft, means by which the shaft is adapted to be rotated by moving part of the sewing machine, a second shaft having a thread, a plurality of gears of different diameters secured to one of the shafts, a plurality of gears of different diameters meshing with the first gears and mounted on the other shaft, selective means to secure a predetermined gear of the last mentioned gears to the shaft on which it is mounted, and a work holder having a tooth for engaging the thread on the second shaft. 70
3. In a feeding device for producing a spiral stitch, a shaft, a second shaft having a thread, a plurality of gears of different diameters secured for rotating with one of the shafts, a plurality of gears of different diameters mounted on the other shaft and meshing with the first gears, selective means to secure a predetermined gear of the second mentioned gears to rotate with the shaft on which it is mounted, a work holder and means by which the thread on the second shaft is adapted to move the work holder relatively to the axis of the second shaft. 75
4. In a feeding device for producing a spiral stitch, a frame with a bearing, adapted to be detachably secured to a sewing machine frame, a shaft journaled in the bearing, a pulley on the shaft normally positioned to be operated by a belt on the sewing machine, a work holder and means mounted on the first frame and operable by the shaft for moving the work holder relatively to the sewing machine frame. 80
5. In a feeding device for producing a spiral stitch, a frame having a horizontal portion normally disposed against the under side of a sewing machine frame and portions with bearings, a shaft journaled in one of the bearings having a member for engagement by a moving part of a sewing machine, a second shaft journaled in another bearing, means by which the second shaft is adapted to be rotated by the first shaft, a third shaft journaled in another bearing, means by which the third shaft is adapted to be rotated by the second shaft, a fourth shaft, means for rotating the fourth shaft by the third shaft at any one of a plurality of different speeds relatively to the third shaft, a work holder and means in connection with the fourth shaft for moving the work holder relatively to the frame. 85
6. In a feeding device for producing a spiral stitch, a frame having a slot and bearings, a shaft journaled in the bearings and provided with a thread, a work holder having a member with a bearing, a stud disposed in the last mentioned bearing and having a tooth normally engaging the thread, resilient means for holding yieldingly the stud with its tooth in engagement with the thread, a button on the stud and a member slidable in the slot and secured to the frame in adjusted positions, having means for engaging the button for moving the stud to a position where its tooth is disengaged from the thread. 90

BORIS TUCKER.
